UTILITY TRAY

Howard C. Riemann, West Allis, Wis., assignor to
The Fulton Company, West Allis, Wis., a corporation of Wisconsin

Application March 1, 1951, Serial No. 14,343

Term of patent 7 years

(Cl. D14—6)

To all whom it may concern:

Be it known that I, Howard C. Riemann, a citizen of the United States, residing at West Allis, in the county of Milwaukee and State of Wisconsin, have invented a new, original, and ornamental Design for Utility Tray, of which the following is a description, reference being had to the accompanying drawing, forming a part thereof.

In the drawing:

Fig. 1 is a top view of a utility tray embodying my new design;

Fig. 2 is a front elevation of the utility tray of Fig. 1;

Fig. 3 is an end view of the same utility tray; and

Fig. 4 is a transverse section through the tray, taken along the irregular line 4—4 of Fig. 1.

The dotted lines shown are for illustrative purposes only.

I claim:

The ornamental design for a utility tray, as shown and described.

HOWARD C. RIEMANN.
